UNITED STATES PATENT OFFICE.

ARTHUR CLARE WEBBER, OF KNOWLESVILLE, NEW YORK, ASSIGNOR OF
ONE-HALF TO HARVEY FRANKLIN FROST, OF SAME PLACE.

DESIGN FOR A CREAM-SEPARATOR.

SPECIFICATION forming part of Design No. 28,816, dated June 7, 1898.

Application filed April 26, 1898. Serial No. 678,917. Term of patent 14 years.

To all whom it may concern:

Be it known that I, ARTHUR CLARE WEBBER, of Knowlesville, in the county of Orleans and State of New York, have invented and produced a new and original Design for a Cream-Separator, of which the following is a full, clear, and exact specification.

Reference is to be had to the accompanying drawings, forming a part of this specification, in which similar characters of reference indicate corresponding parts in both the figures.

Figure 1 is a perspective view of a cream-separator, showing my design; and Fig. 2 is a side elevation of the same.

My design consists of a box A, approximately rectangular in shape and having a

hopper-shaped bottom A' inclined longitudinally and in an upward direction from the front end A² of the box to the rear end A³, as is plainly shown in the drawings, and the 20 said box appears mounted on legs B and has a cover C at the top.

The leading feature of my design consists of a box having a hopper-shaped bottom inclined in a longitudinal direction. 25

I claim—

The design for a cream-separator, as herein shown and described.

ARTHUR CLARE WEBBER.
